UNITED STATES PATENT OFFICE.

PAUL A. BRENDL, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE-PLUG.

1,025,857.

Specification of Letters Patent.

Patented May 7, 1912.

Application filed September 3, 1910. Serial No. 580,358.

To all whom it may concern:

Be it known that I, PAUL A. BRENDL, a citizen of the United States of America, and residing at Bridgeport, in the county of 5 Fairfield and State of Connecticut, have invented a certain new and Improved Fuse-Plug, of which the following is a specification.

My invention relates to fuse plugs and the 10 particular object of my invention is to so locate the fuse with relation to the usual mica-protected opening in the cap that it may be more readily observed than hitherto. In the accompanying drawings, Figure 1 is 15 a vertical section on the lines 1—1, Fig. 2; and Fig. 2 is a plan of a plug with the cap in dotted lines.

My improved plug has the usual insulating body 5 and screw shell side contact 6, as 20 well as the inclosing metallic cover 7 through the large sight aperture 8 in which the fuse chamber 10 may be viewed through the mica disk 9. Instead of the usual central well within the chamber 10, to receive one 25 end of the fuse strip, I provide a contact pin 11, with head 12 at its lower end serving as the center plug contact and connected at its upper end with a metallic strip 13. The latter is angled up over the shoulder 14 on 30 the porcelain and affords a good contact for the end of the fuse strip 15. The latter stretches practically horizontally beneath the cap from the shoulder 14 to the shoulder 17, and the calibration point 16 is thus 35 clearly visible. One end of the fuse is angled down into the well 18 where the solder 19 electrically connects it to the shell 6. The other end is soldered to the connecting strip 13 being offset at 20 to prevent the 40 solder from possibly flowing along the fuse to the calibration point and thus destroying the safety of the fuse. It will be noted further that the recess in which the strip 13 is located is made of such depth that there is 45 no danger of the end of the disrupted fuse which leads to the shell terminal, bending down and contacting with the strip or pin 11 after the fuse is blown, thus establishing an unprotected circuit.

50 I do not limit my invention to the details of the particular construction shown, which may be varied without departing from my invention.

I claim as my invention:

Copies of this patent may be obtained for five cents each, by addressing the "Commissioner of Patents, Washington, D. C."

1. A fuse of the screw plug type comprising an insulating body with fuse chamber, a cover therefor with sight aperture, a center contact, a conductor leading therefrom to one side of the fuse chamber, a shoulder in the opposite side of the fuse chamber forming one side of a side contact well, a side contact communicating with said well, and a fuse passing substantially horizontally across the fuse chamber from said center contact conductor to said shoulder and connected to the side contact in said well, said fuse being offset at the end in contact with center contact conductor to retain the connecting solder, substantially as described. 55

2. A fuse of the screw plug type comprising an insulating body with fuse chamber, a cover therefor with sight aperture, a center contact, a conductor leading therefrom to one side of the fuse chamber, a shoulder in the opposite side of the fuse chamber forming one side of a side contact well, a side contact communicating with said well, and a fuse passing substantially horizontally across the fuse chamber from said center contact conductor to said shoulder and connected to the side contact in said well, said fuse being calibrated at a point sufficiently close to said shoulder to prevent the accidental reestablishment of the fuse circuit through the side contact end of the fuse 85 after the fuse is opened, substantially as described. 70

3. A fuse of the screw plug type comprising an insulating body with fuse chamber, a cover therefor with sight aperture, a center contact, a conductor leading therefrom to one side of the fuse chamber, a shoulder in the opposite side of the fuse chamber forming one side of a side contact well, a side contact communicating with said well, and a fuse passing substantially horizontally across the fuse chamber from said center contact conductor to said shoulder and connected to the side contact in said well, substantially as described. 90

In testimony whereof I have signed my name to this specification, in the presence of two subscribing witnesses.

PAUL A. BRENDL.
